Application September 23, 1953, Serial No. 381,790

1 Claim. (Cl. 2—37)

This invention relates to new and useful improvements and structural refinements in undergarments of the figure confining and molding type, such as for example, girdles, corselets, and the like.

More specifically, this invention primarily concerns itself with certain improvements in the structure and function of the front section of the abdomen encircling portion of such garments, whereby garments constructed in accordance with this invention are better adapted to afford comfort and freedom of movement for the wearer, without impairing or sacrificing their required figure confining and molding characteristics.

As is well known, conventional girdles or corselets have the tendency to compress or constrict the abdominal region of the wearer's body to such extent that they are not only difficult to don or remove and uncomfortable to wear, but also that their confining action interferes considerably with the movements of the wearer while walking, bending or sitting. During the recent years, efforts have been made to overcome these disadvantages, largely by modifying the construction of the abdominal encircling portion so as to include what is known as a "criss-cross" arrangement of relatively independent, overlapped panels which extend diagonally or obliquely to a transverse plane of the garment and, by virtue of their crossed relation and relative independency, permit the wearer to move her thighs with comparative ease.

However, the independent panels in such "criss-cross" arrangements were anchored to the side sections of the garment at vertically spaced points, as necessitated by their diagonal or oblique disposition, and, as a result, regions of the garment below those points of anchorage became ineffective from the standpoint of figure confining and molding, for which the garments were basically intended.

The instant invention, as already mentioned, is primarily adapted to afford comfort and comparative freedom of movement while maintaining the required figure control, this being attained by employing overlapped, relatively independent panels which are anchored to the side sections of the garment in a common plane, coinciding with the lower edge of the garment and without any vertical deviation.

Other features of the instant invention reside in the structure of the panels themselves, this involving various combinations of elastic and non-elastic material arranged so as to cooperate with the anchoring arrangement of the panels for maximum freedom and figure control.

With the above more important objects and features in view and such other objects and features as may become apparent as this specification proceeds, this invention resides in the details of construction and arrangement of parts substantially as shown in the accompanying drawings, wherein:

Figure 1 is a front perspective view, showing the invention embodied in a girdle and in position on the body of a wearer.

2

Figure 2 is a front elevational view of the invention per se.

Figure 3 is a front elevational view, similar to that shown in Figure 2 but with the outer panel of the front section broken away,

Figure 4 is an inside elevational view of the front section, showing the arrangement of the inner panel thereof,

Figure 5 is a cross-sectional detail, taken substantially in the plane of the line 5—5 in Figure 2,

10 Figure 6 is a front elevational view illustrating a modified embodiment of the invention,

Figure 7 is a front elevational view of the subject shown in Figure 6 but with the outer panel broken away,

Figure 8 is a front elevational view of another modified form of the invention, and

Figure 9 is a front elevational view of the subject shown in Figure 8 but with the outer panel broken away.

Like characters of reference are employed to designate like parts in the specification and throughout the several views.

With reference now to the accompanying drawings in detail, it will be observed that the invention has been illustrated as embodied in a girdle. However, it is to be understood that the teachings of the invention may 25 also be applied to other similar garments of the figure confining and molding type, such as for example, corselets, and the like.

Referring particularly to Figures 1—5 of the drawings, the garment as a whole is designated by the general reference numeral 10 and the abdomen encircling portion thereof includes a front section 12 and side sections 14 which are connected to the side edges 16 of the front section in any suitable manner. The invention concerns itself primarily with the structural details of the front section 12, as will be presently explained.

The side edges 16 of the front section 12 are straight and upwardly convergent. The greatest transverse distance between these side edges is at the lower edge of the garment, as indicated diagrammatically at 18. Conversely,

40 the least transverse distance between the side edges is at the waist of the garment, as shown diagrammatically at 20.

The front section 12 is composed of two superposed, 45 overlapping panels, namely, the outer panel 22 and the inner panel 24. These panels have similar lower edges 26, 28, respectively, which are of an inverted, substantially V-shaped configuration and cross each other substantially at the mid-point of the front of the garment. However, it is to be noted that these lower edges are 50 relatively free and detached from each other, the only connection between the panels 22, 24 being at the side edges 16 and at the top of the garment, as will be hereinafter more fully described. It is to be particularly noted that both ends of each of the lower edges 26, 28 55 of the respective panels 22, 24 are coterminous or coincide with the lower ends of the side edges 16 at the points 30 which, in turn, are disposed in the normal plane of the lower edge of the front section of the garment. By virtue of their inverted, substantially V-shaped configuration, the lower edges 26, 28 have vertices 32, 34, respectively, which are spaced upwardly from the plane of the points 30 and inwardly from the side edges 16.

When the garment is placed in position on the wearer's body as illustrated in Figure 1, the recessed lower portions of the panels 22, 24, as defined by the inverted, substantially V-shaped edges 26, 28, will afford a substantial amount of freedom of movement for the thighs of the wearer while walking, bending or sitting. At the same time, inasmuch as the terminal points 30 of the lower edges 26, 28, are disposed at the lower ends of the side edges 16, the anchorage of these points to the side sections 14 is at the lowermost plane of the front section 12.

and in that manner the figure molding ability of the garment is not materially affected by the freedom of movement which the panels 22, 24 afford.

Customary hose suspenders 35 depend from the rear portion of the garment, while similar suspenders 36 are attached to the lower edges 26, 28 of the panels 22, 24, inwardly of and somewhat above the anchor points 30. It will be also noted that the garment may be provided with a conventional slide fastener 38 at either one of the side sections 14, if so desired.

The freedom of movement facilitated by the particular, already described arrangement of the panels 22, 24 is enhanced by the specific structure of the panels themselves. As is best shown in Figures 1 and 2, the outer panel 22 consists of an upwardly tapered region or strip of elastic material 40 having an arcuate inner edge 42 connected to a downwardly tapered region 44 of non-elastic material which, in turn, is connected to an arcuate edge 46 of a second, upwardly tapered elastic strip 48. The latter, in turn, is attached to a non-elastic region 50 which, although constituting a component of the front section 12, may be in the form of an integral extension of the adjacent side section 14, if so desired.

The inner panel 24, best shown in Figures 3 and 4, consists of an elastic strip or region 52 which is interposed between two regions 54, 56 of non-elastic material. The upper edges of the regions 54, 56, terminate somewhat below the waistline as indicated at 58, 60, so that, in effect, the sole connection between the inner and outer panels at the upper edge of the front section 12 is between the regions 52 and 44.

It will be observed that in all instances the elastic regions of the panels 22, 24 extend upwardly from the respective lower edges 26, 28 of the panels and are yieldable circumferentially of the garment, as indicated by the arrows 62.

With reference to a modified form of the invention illustrated in the accompanying Figures 6 and 7, the general arrangement of the front section panels is the same as that already described, the only difference being in the specific structure of the panels themselves. Thus, in the modified form of the garment designated generally by the reference numeral 70 in Figures 6 and 7, the structure of the outer panel 22a is identical to that of the panel 22, while the structure of the inner panel 24a is the same as that of the panel 22a, but is reversed, side for side, so as to attain the desired overlapping arrangement and the crossing of the lower edges of the two panels, as already explained. For simplicity of designation, the component parts of the panel 22a have been identified by the same reference numerals as those of the panel 22 and the corresponding parts of the panel 24a have been suffixed by the symbol (').

With reference now to the further modified embodiment of the invention illustrated in the accompanying Figures 8 and 9 and designated generally by the reference numeral 80, here again the arrangement of the front section panels is substantially the same and only the specific structure of the panels themselves is modified.

In this instance, the outer panel 82 consists of a rela-

tively narrow elastic region or strip 84 which is interposed between two regions 86, 88 of non-elastic material. Similarly, the inner panel 90 comprises an elastic strip 92 interposed between two regions 94, 96 of non-elastic material. As will be observed, the vertices of the lower edges 98 of the two panels need not be sharp or pointed as in the previously disclosed embodiments, but may be of a rounded configuration, as shown at 100.

While the side sections 14 of the embodiments 10 and 10 70 are generally non-elastic, the side sections 14b of the embodiment 80 are of elastic material, yieldable circumferentially of the garment, so as to compensate for the relatively smaller amount of elastic material 84, 92 used in the front section panels of the embodiment 80.

While in the foregoing there have been shown and described the preferred embodiments of this invention, it is to be understood that various other modifications may be resorted to, such as may fall within the spirit and scope of the appended claim.

What is claimed as new is:

In an undergarment of the forso confining and molding type, a front section defined by a pair of straight and upwardly convergent side edges having the greatest transverse distance therebetween at the bottom of the front section, said front section comprising a pair of superposed panels having coextensive side edges secured together at the side edges of the front section, the side edges of both said panels terminating at their lower ends at the lower ends of the side edges of the front section, each panel having an inverted substantially V-shaped lower edge extending upwardly from the lower end of one of the side edges of the front section and then downwardly to the lower end of the opposite side edge thereof, said lower edge of each panel having its highest point disposed transversely intermediate the side edges of the front section and spaced further away from one side edge thereof than from the other, each panel having a relatively small substantially triangular lower edge region at one side and a relatively large substantially triangular lower edge region at the other side of said highest point, the lower edges of said panels being crossed and detached from each other and the small lower edge region of each panel being in superposed relation with the large lower edge region of the other panel, whereby to reinforce the same and whereby to anchor both ends of the lower edges of both panels at the bottom of the respective opposite sides of the front section.
